REAGENT FEEDER

Louis D. Mills, Palo Alto, Calif., assignor to The Merrill Company, San Francisco, Calif., a corporation of California

Application July 25, 1938, Serial No. 221,161

6 Claims. (Cl. 221—97)

This invention relates generally to liquid reagent feeders such as are employed to supply measured quantities of a liquid reagent for various industrial processes.

It is an object of the invention to provide apparatus of the above character which will have both mechanical simplicity and a high degree of accuracy.

Another object is to afford an improved reagent feeder of the revolving bucket type which will eliminate objectionable splashing or dripping of reagent.

Further objects of the invention will appear from the following description in which the preferred embodiment of the invention has been set forth in detail in conjunction with the accompanying drawing.

Referring to the drawing:

Fig. 1 is a side elevational view, illustrating apparatus incorporating the present invention.

Fig. 2 is an end view partly in section of the apparatus shown in Fig. 1.

Fig. 3 is an enlarged sectional view taken along the line 3—3 of Fig. 2.

The apparatus as illustrated in the drawing consists of a suitable container 10, for holding a quantity of liquid reagent. The material from which this container is made may vary in different instances, but for chemicals which may react with ordinary metals, it is desirable to use a suitable wood such as redwood. Above the container there is a horizontal rotatable shaft 11, carried by journals 12. Any suitable source of power can be employed to drive shaft 11 at a constant speed, such as a constant speed electric motor 13, connected to shaft 11 through the pulleys 14 and 15 and belt 16.

Arms 17 are fixed to one end of the shaft 11, and the free ends of these arms carry small reagent cups or buckets 18. The mounting of each cup 18 to its associated arm 17 is such that the cup can be individually adjusted about a horizontal axis. Thus in the instance illustrated a bolt 19 forms the adjustable attachment, and the cup is held spaced with respect to arm 17, by the collar or spacer 21.

To receive the discharge of liquid from cups 18, a circular member 22 is provided, and the periphery of this member is grooved to form a trough 23. This member can also be formed of wood, and it is mounted concentric with respect to shaft 11, with its upper portion underlying the path of movement of the cups 18. With the arrangement illustrated, member 22 is attached

to the wooden cross member 24, which in turn is attached to the side walls of the container 10.

The discharge of reagent from the apparatus is by way of a discharge pipe or spout 25. This pipe has a swivel attachment 26 to member 22, as shown in Fig. 1, and its inner end is in communication with a duct 27, leading upwardly and communicating with the trough 23 in member 22. The swivel attachment 26 permits angular adjustment of pipe 25 to various positions as indicated in Fig. 1.

Operation of the apparatus described above, is as follows: The shaft 11 is driven at a constant speed, and cups 18 move in a circular path and periodically dip into the liquid in container 10. As a cup moves upwardly out of the liquid it is filled or substantially filled with liquid, and this liquid is carried upwardly until the cup approaches the upper part of the path of movement. Here as the cup tilts the liquid is gradually discharged into the trough 23, and at least a part of the discharge occurs while the cup is progressing over the uppermost point *a* of the trough 23. Thus during the time that each cup is discharging, a part of the discharge occurs before the cup reaches the uppermost limit of its movement, or in other words to the right of point *a*, while the remainder of the discharge takes place after the cup has passed the top of its movement, or in other words to the left of point *a* as viewed in Fig. 1. Thus a part of the discharge from each cup flows forwardly to enter duct 27, while another part flows backwardly and is returned to the container.

The rate of feed from pipe 25 can be adjusted in two different ways. A change in the angular setting of the cups with respect to the arms 17, affords an approximate adjustment, because it controls the ratio between that part of the reagent which flows forwardly toward the duct 27, and that part which flows backwardly into the container.

A finer or more delicate adjustment can be had by changing the angular setting of pipe 25. With this pipe tilted downwardly (see lowermost dotted line portion of Fig. 1) substantially all of the liquid flowing toward it down the trough 23 is received by duct 29 and discharged. When pipe 25 is tilted upwardly, as for example to the solid line position of Fig. 1, duct 27 acts as a liquid well, and over a substantial range of adjustment in the proximity of such position, varying amounts of the liquid received by duct 27 are caused to overflow and are returned to the container. Under such conditions the level of liquid

in duct 27 remains constant over a substantial range of adjustment, and for a given setting of pipe 25 the rate of feed will remain constant to a high degree of accuracy.

The apparatus described above can be used for a wide variety of liquid reagents, wherever a constant rate of feed is desired. It has been used to advantage in cyanide precipitating processes, for feeding of solutions of salts like lead nitrate or lead acetate, to cyanide solution, for the purpose of aiding effective precipitation with zinc. In addition to the advantages of mechanical simplicity and accuracy, the apparatus operates without splashing or dripping of the reagent, such as is experienced with prior reagent feeders of the rotatory bucket type. This is because the discharge from the cups or buckets is received by the trough 23 without splashing, and the flow back to the container occurs entirely over the periphery of member 22. Splashing of liquid reagent is undesirable not only because it may involve some inaccuracy in the rate of feed, but also because it results in rusting or corrosion of metal parts.

I claim:

1. In a reagent feeder, a liquid container, a cup, means forming a rotatable mounting for the cup whereby the cup moves in a circular path, the circular path being such that the cup periodically dips into liquid in the container, means forming a flow dividing trough underlying the upper portion of the path of movement of the cup, the trough being sloped downwardly in opposite directions from an uppermost intermediate point, and means for removing liquid reagent flowing down said trough at one side of said medial point, the portion of said trough at the other side of said medial point providing a return path to said container.

2. In a reagent feeder, a liquid container, a cup, means forming a rotatable mounting for the cup about a substantially horizontal axis whereby the cup is moved in a circular path in an upright plane, the spacing of said cup from said axis and the spacing of said axis relative to said container providing a path of movement of the cup causing it to periodically dip into liquid in the container, a substantially circularly contoured member disposed within the path of movement of said cup and extending into the liquid in said container, said member having a grooved periphery forming an arcuate flow dividing trough underlying the upper portion of the path of movement of the cup, and means for removing liquid from one point on the trough disposed below the uppermost point of the same, the other side of said trough providing a return path to said container.

3. In a reagent feeder, a liquid container, a cup, means forming a rotatable mounting for the cup whereby the cup is caused to move in a circular path extending into said container, the circular path being in an upright plane whereby for the lower portion of said path the cup dips into liquid in the container, said mounting means having an adjustable connection with said cup enabling individual angular adjustment of the cup about a horizontal axis, a flow di-

viding trough underlying the upper portion of the path of movement of the cup, and means for removing solution from said trough at a point below the uppermost portion of the same, the angular adjustment of said cup providing for control of the beginning of discharge of liquid therefrom with respect to said uppermost portion.

4. In a reagent feeder, a liquid container, a cup, means forming a rotatable mounting for the cup to provide a path of movement for the cup extending into the container whereby the path of movement of the cup causes it to periodically dip into liquid in the container, a member forming a flow dividing trough underlying the upper portion of the path of movement of the cup, and means for removing reagent from one portion of the trough, said last means including a generally upright duct formed in said member and having its upper end communicating with the trough, and a discharge pipe having one end of the same connected to the lower portion of said duct, the angular position of said pipe with respect to the horizontal being adjustable to regulate liquid flow from the duct to the pipe.

5. In a reagent feeder, a liquid container, a cup; means mounting said cup for movement in a circular path in an upright plane with the lower portion of said path extending into the liquid in said container, said mounting means including an adjustable support for said cup to enable change in its angular position thereon, and an arcuate flow dividing trough underlying and closely adjacent the upper portion of said path for receiving liquid from said cup, one portion of said trough having means for removing solution from a point below the uppermost portion thereof and the other portion of said trough providing a return path to said container, whereby the angularly adjusted position of said cup controls the amount of liquid therein delivered to said removing means and the amount returned to said container.

6. In a reagent feeder, a liquid container, a cup; means mounting said cup for movement in a circular path in an upright plane with the lower position of said path extending into the liquid in said container, said mounting means including an adjustable support for said cup to enable change in its angular position therein, an arcuate flow dividing trough underlying and closely adjacent the upper portion of said path for receiving liquid from said cup, one portion of said trough having means for removing solution from a point below the uppermost portion thereof and the other portion of said trough providing a return path to said container, whereby the angularly adjusted position of said cup controls the amount of liquid therein delivered to said removing means and the amount returned to said container, and a discharge pipe leading from said removing means and mounted for adjustment with respect to the horizontal to regulate liquid flow therethrough.

LOUIS D. MILLS.
